UNITED STATES PATENT OFFICE.

EDWARD BAER, OF NEW YORK, N. Y.

COOLING DEVICE.

1,218,827.

Specification of Letters Patent. Patented Mar. 13, 1917.

Application filed June 28, 1916. Serial No. 106,442.

To all whom it may concern:

Be it known that I, EDWARD BAER, a citizen of the United States, residing at New York, in the county and State of New York, have invented certain new and useful Improvements in Cooling Devices, of which the following is a full, clear, and exact specification.

This invention relates to devices for cooling liquids and semi-solid masses, and it has for its object to provide apparatus of this kind which is very simple in construction and inexpensive to manufacture. Another object is to provide improved means for covering the outer compartment of the device in which the ice is designed to be placed, said cover being self-sustaining in a raised or opened position as well as when closed. A further object is to produce a device of this kind which may be conveniently carried by hand, making it especially useful for picnic parties.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is an elevation of a cooling device constructed substantially in accordance with the present invention, the cover for the outer compartment being shown in closed position, as when the device is packed ready for transportation.

Fig. 2 is a central vertical section of the device, taken on the line II—II of Fig. 1, showing the cover for the outer compartment raised, or opened, as when the ice is being placed in said compartment, and

Fig. 3 is a plan view of the cooling device.

As illustrated, the device comprises an outer cylindrical vessel 1 and an inner concentrically arranged container 2 both of which may be made of any suitable material, such as fiber or wood. The inner container is supported away from the bottom of the outer vessel by suitable brackets 3 which are soldered, riveted or otherwise secured to both parts so that the outer vessel may be raised with the inner compartment by grasping the bail 4 secured to the upper end por-

tion of said inner compartment. Liquids or semi-solids may be placed in the container 2 for cooling by means of ice packed in the outer compartment 5 between the container 2 and the outer vessel 1. The container 2 is provided with a suitable cover 6 fitting its open upper end with sufficient frictional resistance to normally hold it in place during transportation.

The inner container 2 extends well above the outer vessel 1, and around the upwardly projecting portion of said container there is arranged a cover 7 of ring-shaped formation for closing the outer compartment 5. The cover 7 may also be made of fiber, wood or any other suitable material, and is fitted closely around and frictionally engages the outer surface of the projecting portion of the container 2 so that when raised or opened, as illustrated in Fig. 2, said cover will be self-sustaining owing to the frictional contact between its inner edge and the outer surface of the container. The cover 7 is provided with a depending flange 8 which is also adapted to frictionally engage the marginal portion of the outer surface of the vessel 1 for further insuring the retention of the cover in closed position when the device is in use. It will be understood, of course, that the frictional contact between the inner edge of the cover 7 and the outer surface of the container 2 will also serve to hold said cover in closed position as well as in raised position. Because of the fact that the cover 7 is self-sustaining when raised, as just explained, the packing of the ice in the outer compartment 5 is greatly facilitated, and time is saved by reason of the fact that said cover does not have to be entirely removed or separated from the cooling device.

While I have explained that my invention is especially useful as a cooling device for picnic parties, I do not wish to be limited to any particular use, for it is obvious that such articles as beer cans, butter dishes, cream and milk coolers, and many other household articles, may be constructed substantially as herein disclosed and claimed.

Having thus described my invention, what I claim as new and desire to secure by Letters Patent of the United States is:

1. In a cooling device, the combination with an outer vessel, of an inner container extending above said vessel, and a ring-shaped cover for the outer vessel fitted

- around the extended portion of the container, and slidable thereon for opening and closing said vessel.
2. In a cooling device, the combination with an outer vessel, of an inner container extending above said vessel, and a cover for the vessel fitted around and frictionally engaging the outer surface of the container, whereby said cover is self-sustaining when 10 raised.

3. In a cooling device, the combination with an outer vessel, of an inner container extending above said vessel, a cover for the vessel frictionally engaging the outer surface of the container, and a depending 15 flange on the cover for frictionally engaging the outer surface of the vessel.

In testimony whereof I have signed my name to this specification.

EDWARD BAER.
